U.S. Appl. No. 29/770,348, filed Feb. 11, 2021, Rory Frederick McGarry et al.

Primary Examiner — Charles D Hanson

(74) Attorney, Agent, or Firm — John M. Lipchitz

(57) **CLAIM**

The ornamental design for a shaving razor organizer, as shown and described.

DESCRIPTION

FIG. 1 is a first perspective view of a design for a shaving razor organizer of the present invention;

FIG. 2 is a rear view thereof;

FIG. 3 is a front view thereof;

FIG. 4 is a right side view thereof;

FIG. 5 is a left side view thereof;

FIG. 6 is a top view thereof;

FIG. 7 is a bottom view thereof; and,

FIG. 8 is a second perspective view thereof.

The dash broken lines are directed to the environment and are for illustrative purposes only and form no part of the claimed design.
